TARGET APPARATUS FOR USE WITH KINEMATOGRAPHS.

1,075,894.

Specification of Letters Patent.

Patented Oct. 14, 1913.

Application filed November 12, 1912. Serial No. 730,970.

To all whom it may concern:

Be it known that we, BENJAMIN WILLIAM BATES, HENRY WELDON KELLY, and DOUGLAS HAYNES CORBIN, subjects of the King 5 of Great Britain, residing at 128 Great Colmore street, Birmingham, 36 St. Peters road, Handsworth, Birmingham, and 80th Lionel street, Birmingham, in the county of Warwick, England, respectively, have invented 10 a new and useful Target Apparatus for Use with Kinematographs; and we do hereby declare the following to be a full, clear, and exact description of the same.

Our invention comprises improvements in 15 target apparatus for use with kinematographs and the like and refers more particularly to that class in which a picture is produced upon a perforatable screen, the screen having a light at the rear which is 20 visible through the bullet hole when a shot passes through the screen, the said hole thus indicating the position of the hit, though the invention may be employed in conjunction with any other suitable form of target. Such 25 a screen forms the subject of a prior Patent No. 1,027,371 granted to Benjamin William Bates and A. T. C. Hale, the screen being so constructed that a puncture made by the shot may be readily obliterated.

30 Of the various embodiments of which the invention is capable we have selected for illustration a specific embodiment, the structure of which at the present time we consider to exhibit the different features of the 35 invention in the most convenient manner and effective form.

In the accompanying drawings:—Figure 1 is a diagrammatic view showing the various parts of the apparatus with their electrical connections. Fig. 2 is a side elevation of the breaking or motion arresting device carried by the kinematograph. Fig. 3 is a side elevation with beater shaft broken at A—B, on Fig. 4 thus showing spring controlled stop. Fig. 4 is a plan, while Fig. 5 is a plan showing the arrangement for operating the screen.

In carrying our invention into practice as shown upon the accompanying drawings, on 50 the beater shaft 1 of the kinematograph we provide a brake drum 2, which might be provided on another shaft; underneath said brake drum are arranged two electromagnets 3 having an armature 4 pivoted in a suitable

bracket and normally held out of contact 55 with the magnets 3 by a spring 4¹. Around the brake drum 2 is a band brake 5 one end of same being attached to a suitable fixed point and the other end attached to the armature 4 so that when the magnets are energized the 60 band 5 is drawn tight around the brake drum 2. It is well known that the movement of kinematograph pictures is intermittent, and the object of the following contact device is to make it impossible for the stopping circuit to be completed while the film is moving, and thus to prevent the possibility 65 of a picture being half on the screen it being essential that the kinematograph should only be stopped when a complete picture 70 is exposed. To insure this we employ a wipe contact 6 on the brake drum 2 and contact 7 these contacts being in the same circuit as the magnets 3. The circuit containing the magnets 3 can only be completed 75 when the wipe contact 6 is in contact with the spring contact 7 thereby energizing the magnets 3 and applying the band brake 5 to the drum 2 and thus stopping the machine without shock. The wipe contact 6 80 being at a particular point on the drum and in a particular relation to the beaters it insures that the circuit can only be completed and the kinematograph stopped when a full picture is exposed.

85 To insure the kinematograph stopping at the correct place in the event of the wipe contact 6 over-running the spring contact 7 before the kinematograph is completely stopped, we provide a pillar contact 8 which is in the same circuit as the magnets 3 and 10. The pivoted armature 4 is preferably provided with a spring contact 9 which is so arranged that when the armature 4 is in its normal position the spring contact 9 95 is slightly out of contact with the pillar contact 8. Should the contacts 6 and 7 be broken before the kinematograph is properly stopped, the slight movement of the armature 4 which it would have in the event 100 of the contacts 6 and 7 only momentarily engaging each other, would cause the spring contact 9 to engage the pillar contact 8 thereby completing the circuit and stopping the kinematograph in manner hereinafter 105 explained.

As a further safeguard for stopping the kinematograph we preferably provide two

2

magnets 10 in the same circuit as the magnets 3 and provided with a pivoted armature 11, so arranged that at the same time as the magnets 3 are energized the magnets 10 5 are also energized thereby drawing down the armature 11, the end of same being so arranged that if the band brake 5 is unable to take up the momentum of the machine in time, a sure stop is provided in the correct place by means of the end of the armature 11 abutting against a spring controlled stop 13 on the drum thereby stopping the machine without shock. On the beater shaft 1 is also provided a suitable friction 10 or other clutch, the one shown being of the electromagnetic type. The part 12 is driven by an electric motor or any other suitable means employed for driving the machine. The clutch is so arranged that when the 15 film is running the coil of said clutch is in circuit thereby energizing the magnet and driving the part 13 which is keyed to the shaft 1. On the firing of the gun the circuit containing the clutch is broken thereby 20 allowing the part 12 to run free. The circuit containing the magnets 3 and 10 is energized thereby stopping the machine as heretofore explained. On firing a shot from the rifle or the like a vibratory current is 25 set up by the diaphragm of the microphone 14 or equivalent device vibrating, owing to the sound waves, said microphone being connected by the wires 15 to the primary of the transformer 16, a battery or other source of 30 energy 17 supplying the current for this circuit. The microphone is preferably located in a conical sound receiver.

It will be obvious that the variations or 40 vibrations of the current in the primary circuit are extremely feeble being the nature of those used in telephony and it is therefore essential that the relay shall be of an extremely sensitive construction in order to respond to these feeble currents. A suitable 45 form of relay forms the subject of a prior application for a patent Serial No. 690,194 of Hans Von Kramer and Doctor Gisbert Kapp. Such relays are of the polarized type and employ a steel reed having 50 its vibrating end located between the extremities of the polar extension around which wire forming part of the controlling circuit is wound. These windings may 55 form part of the circuit in which the microphone is located or as stated they may form part of the secondary circuit of an induction coil or transformer or they may be otherwise influenced by the circuit in which the microphone is located.

60 The mechanism may be so arranged as to respond only to the sound waves above a certain predetermined periodicity and in certain circumstances to respond to sound waves of a known periodicity which is ef-

fected by tuning the vibratory reed to correspond with the vibrations of the microphone diaphragm set up by the sound waves in question.

Connected to the secondary of the transformer 16 is a relay 18 said relay being of the kind described in Kramer and Kapp specification Serial No. 690,194. On the vibration of the diaphragm of the microphone 14 a vibrating current is set up in the primary of the transformer 16 thereby inducing a vibrating current in the relay 18. The flanking springs 19 of the relay 18 are provided with contact pieces 20 so arranged that when the armature 21 of the relay vibrates a circuit which will be hereinafter described is broken by the contacts 20 being separated.

Connected to the contact springs 19 are wires 22 and battery 23 which is also connected to the relay magnet 24. Normally the coils of the relay magnet 24 are energized thereby holding the armature 25 in position and completing a circuit which keeps the magnetic clutch energized in manner hereinafter described.

On an induced current being set up in the transformer 16 the relay 18 is energized thereby breaking the contacts 20 and momentarily deenergizing the relay 24, the armature 25 then dropping under the influence of the spring 26 and completing another two circuits through the contacts 27 and 28, thereby energizing the magnet 29 which holds the armature 25 on the contacts 27, 28, and also energizing the solenoid 49 as hereinafter explained.

The magnet 29 is energized in the following manner:—Current is taken from the battery 30 along wires 31, 32, frame 33 of the relay 24, armature 25, contact 28, through the coil of the magnet 29, wire 34 spring contacts 35, 36 wires 37, 38, and back to battery 30.

When the armature 25 is in its normal or raised position it is in contact with stop 39 thereby completing a circuit and energizing the magnetic clutch. The circuit for normally holding the clutch in engagement is as follows:—battery 30, wires 31, 32, frame 33 of relay 24, armature 25, contact 39, wire 40, contact 41, movable contact 42, wire 43, wipe contact 44, annular ring 45 which is insulated from the part 12 by means of insulation 46. The one end of the coil in the clutch is connected to the ring 45, the other end being connected to the part 12 of the machine where it is earthed and then back to the battery through wire 48. On the armature 25 disengaging the stop 39 the circuit is broken thereby deenergizing the magnet of the clutch and allowing the part 12 to run free. At the same time as the armature 25 comes in contact with the stops 27, and

28 the magnets 3 and 10 are energized through the wire 47 thereby drawing the armatures 4 and 11 into their attracted position applying the band brake 5 to the drum 2 and stopping the machine. The circuit for energizing the magnets 3 and 10 is as follows:—When the contact 28 is engaged by the armature 25, the current passes from battery 30, wires 31, 32, frame 33, of relay 10 24, relay armature 25, contact 28, wire 47, through coils 3 and 10, spring contact 7 and wipe contact 6 then through the machine which is earthed, wire 48 to battery 30. In the event of the contacts 6 and 7 being broken before the kinematograph is stopped, the aforesaid circuit is momentarily completed thereby giving the armature 4 a partial movement and engaging the contacts 8 and 9 and completing the circuit for stopping the machine in the correct place in the following manner:—The current would pass from the battery 30, along wires 31, 32, frame 33 of relay 34, relay armature 25, contact 22, wire 47 through coils 3 and 10, wires 47^a and 47^b which are connected to spring contact 7, pillar contact 8, spring contact 9 carried by the armature 4 which is earthed to the frame of the kinematograph, wire 48 to battery 30.

30 As illustrated the screen is according to the prior Patent No. 1,027,371 wherein two sheets of perforated paper are employed, relative movement between the two sheets serves to close the puncture and obliterate 35 the effect of the shot. This relative movement is automatically effected simultaneously with the restarting of the picture projecting device.

On the falling of the armature 25 a further 40 circuit through contact 27 is completed wherein the solenoid 49 is energized thereby lifting up the movable core 50, said core being controlled in its movement by a dash pot 51 or any other suitable device. On the 45 core 50 rising the circuit controlling the magnetic clutch is broken by the movable contact 42, disengaging from the contacts 41, and remains broken until the return of the core 50 replaces contact 42, the member 50 12 being then allowed to continue running while the other part of the picture projecting device is stopped. The core 50 still continuing its upward movement completes a further circuit to actuate the screen, the 55 circuit for operating the screen being as follows:—The core 50 has risen until the movable contact 42 has completed the circuit by engaging the contacts 53. The current is taken from the battery 30 along the wire 31, contacts 53 movable contact 42, wire 52, to solenoid 54, thereby actuating the armature 55. The end of the armature 55 is in the form of a "free wheel clutch" 54 mounted on the shaft 63 so arranged that on the sole-

noids 54 being energized the armature 55 is drawn down thereby rotating the pinion wheel 64 which engages a further gear wheel 65 carried by the shaft 68, said shaft 68 is connected to the store roll 58, all being so arranged that when the solenoids 54 are energized the armature 55 is drawn downward and the shaft 63 rotated thereby driving the gear wheel 65 through the pinion 64 and rotating the store roll 58 and thereby obliterating the shot holes.

When the solenoids 54 are deenergized the armature 55 returns to its original position under the action of the spring 69, the clutch 54 having a free movement on its return. The pawl 66 engages the tooth wheel 67 and prevents backward rotation of the store roll 58. By this means the shot holes are obliterated in manner described in the prior patent of Benjamin William Bates and A. T. C. Hale No. 1,027,371. Around 85 part of the supply roll of the screen we arrange a suitable band brake so as to prevent the paper too freely unwinding.

On the core 50 reaching the top of the solenoid 49, it engages a plunger 60 thereby breaking the contacts 35, 36 deenergizing the magnet 29 and allowing the armature 25 to return to its normal position thereby completing the circuit for energizing the magnetic clutch and restarting the picture 95 projecting apparatus, ready for a further shot to be fired on the return of the core 50 and contact 42.

The duration of the time for which the machine is stopped is controlled by a dash 100 pot 51 only allowing the core to rise slowly and break contacts 35, 36, the return being practically instantaneous, as the piston 61 is provided with a one way valve 62. A suitable time for stopping is about three 105 seconds but this may obviously be varied as required.

What we claim then is:—

1. In target apparatus for use with kinematographs and the like, the combination of 110 a picture projecting device; a target screen onto which the picture is projected; and means actuated by sound waves whereby the movement of the picture projecting device is arrested.

2. In target apparatus for use with kinematographs and the like, the combination of 115 a picture projecting device; a target screen onto which the picture is projected; and means actuated by the sound arising 120 from the discharge of a fire arm whereby the movement of the picture projecting device is arrested.

3. In target apparatus for use with kinematographs and the like, the combination of 125 a picture projecting device, a target screen onto which the picture is projected; a member mounted to vibrate under the influence

of sound waves; and means actuated by the vibrations of said member whereby the movement of the picture projecting device is arrested.

5. 4. In target apparatus for use with kinematographs and the like, the combination of a picture projecting device; a target screen onto which the picture is projected; a member mounted to vibrate under the influence 10 of the sound arising from the discharge of a fire arm; and means actuated by the vibrations of said member whereby the movement of the picture projecting device is arrested.

15. 5. In target apparatus for use with kinematographs and the like, the combination of a picture projecting device; a target screen onto which the picture is projected; a source of electric current in circuit with apparatus 20 on said picture projecting device; means for varying the current in said circuit under the influence of sound waves; and means actuated by the variations in the electric current whereby the movement of the picture 25 projecting device is arrested.

6. In target apparatus for use with kinematographs and the like, the combination of a picture projecting device; a target screen onto which the picture is projected; a source 30 of electric current in circuit with apparatus on said picture projecting device; means for varying the current in said circuit under the influence of sound waves; a member mounted to vibrate under the influence of sound 35 waves; means whereby the vibrations of the said member are caused to vary the current in the electric circuit; and means actuated by the variations in the electric current whereby the movement of the picture 40 projecting device is arrested.

7. In target apparatus for use with kinematographs and the like, the combination of a picture projecting device; a target screen onto which the picture is projected; a source 45 of electric current in circuit with apparatus on said picture projecting device; means for varying the current in said circuit under the influence of sound waves; a microphone also in said electric circuit arranged to vibrate under the influence of sound waves and to thereby cause a variation in the current in said electric circuit; and means actuated by the variations in the electric current whereby the movement of the picture 50 projecting device is arrested.

55. 8. In target apparatus for use with kinematographs and the like, the combination of a picture projecting device; a target screen onto which the picture is projected; a microphone the diaphragm of which is arranged to vibrate under the influence of sound waves; a transformer having its primary in circuit with said microphone; a relay device in circuit with and actuated by

the secondary of said transformer; and an 65 electric circuit controlled by said relay and through which the vibrations of the microphone diaphragm under the influence of sound waves are caused to arrest the movement of the picture projecting device. 70

9. In target apparatus for use with kinematographs and the like, the combination of a picture projecting device; a plurality of rollers; a length of paper passing around same and presenting a screen of double 75 thickness; a source of light at the rear of said screen; a screen controlling magnet; means whereby when the magnet is energized the paper is automatically advanced; a microphone the diaphragm of which vibrates under the influence of the sound waves; a transformer the primary of which is in circuit with said microphone; a relay device in circuit with the secondary of said transformer; a magnetic clutch device on the 80 picture projecting device for normally connecting the said picture projecting device to the source of power; an electromagnet; a source of electrical energy in circuit with said magnet; a contact device also in circuit 85 with said magnet and normally closed but arranged to open when the relay is actuated; an armature actuated by the deenergizing of the magnet so as to deenergize and release the magnetic clutch on the picture projecting device; a band brake on said picture projecting device; an electromagnet controlling said band brake and actuated when the aforementioned armature is released; an electromagnet for controlling the movement 90 of the paper screen; means for energizing the said magnet at a predetermined time after the stopping of the picture projecting device and to thereby obliterate the shot holes; and means for restoring the apparatus 95 to its normal condition.

10. In target apparatus for use with kinematographs and the like, the combination of a picture projecting device; a plurality of rollers; a length of paper passing around 110 same and presenting a screen of double thickness; a source of light at the rear of said screen; a screen controlling magnet; means whereby when the magnet is energized the paper is automatically advanced; and means 115 actuated by sound waves whereby the movement of the picture projecting device is arrested.

11. In target apparatus for use with kinematographs and the like, the combination of 120 a picture projecting device; a target screen onto which the picture is projected; a microphone the diaphragm of which vibrates under the influence of sound waves; a transformer the primary of which is in circuit 125 with said microphone; a source of light at the rear of said screen; a screen controlling magnet; a magnetic clutch device on the

- picture projecting device for normally connecting the said picture projecting device to the source of power; an electromagnet; a source of electrical energy in circuit with said magnet; a contact device also in circuit with said magnet and normally closed but arranged to open when the relay is actuated; an armature actuated by the deenergizing of the magnet so as to deenergize and simultaneously with the re-starting of the picture projecting device. 65
17. In target apparatus for use with kinematographs and the like, the combination of a picture projecting device; means for automatically stopping the picture projecting device when a fire arm is actuated; means for re-starting the picture projecting device after a predetermined period of rest; a target screen; and means for automatically operating the screen to obliterate the shot holes. 75
18. In target apparatus for use with kinematographs and the like, the combination of a picture projecting device; a plurality of rollers; a length of paper passing around same and presenting a screen of double thickness; a source of light at the rear of said screen; a screen controlling magnet; means whereby when the magnet is energized the paper is automatically advanced; a relay device actuated when the shot is fired; a magnetic clutch device on the picture projecting device for normally connecting the said picture projecting device to the source of power; an electromagnet; a source of electrical energy in circuit with said magnet; a contact device also in circuit with said magnet and normally closed but arranged to open when the relay is actuated; an armature actuated by the deenergizing of the magnet so as to deenergize and release the magnetic clutch on the picture projecting device; a band brake on said picture projecting device; an electromagnet controlling said band brake actuated when the aforementioned armature is released. 80
19. In target apparatus for use with kinematographs and the like, the combination of a picture projecting device; a target screen onto which the picture is projected; a magnetic clutch on said picture projecting device; a band brake on said picture projecting device; and means actuated by sound waves whereby said magnetic clutch is deenergized and the band brake applied for the purpose of arresting the movement of the picture projecting device. 85
20. In target apparatus for use with kinematographs and the like, the combination of a picture projecting device; means for automatically stopping the picture projecting device when a fire arm is actuated; and means for automatically restarting the picture projecting device after a predetermined period of rest. 90
21. In target apparatus for use with kinematographs and the like, the combination of a picture projecting device; means for controlling the movement of said picture projecting device; means for automatically stopping the picture when a fire arm is actuated without stopping the driving means; and means for automatically re-starting the picture projecting device after a predetermined period of rest. 95
22. In target apparatus for use with kinematographs and the like, the combination of a picture projecting device; means for automatically stopping the picture projecting device when a fire arm is actuated; a soleiloid energized when the picture projecting device is stopped for the purpose of automatically re-starting the picture projecting device; and a dash pot for controlling the duration of the period of rest. 100
23. In target apparatus for use with kinematographs and the like; the combination of a picture projecting device; means for automatically stopping the picture projecting device when a fire arm is actuated; means for re-starting the picture projecting device after a predetermined period of rest; a target screen; and means for automatically operating the screen to obliterate the shot holes. 105
24. In target apparatus for use with kinematographs and the like, the combination of a picture projecting device; a relay device actuated when the shot is fired; a magnetic clutch device on the picture projecting device for normally connecting the said picture projecting device to the source of power; an electromagnet; a source of electrical energy in circuit with said magnet; a contact device also in circuit with said magnet and normally closed but arranged to open when the relay is actuated; an armature actuated by the deenergizing of the magnet so as to deenergize and release the magnetic clutch on the picture projecting device; a band brake on said picture project- 110
25. In target apparatus for use with kinematographs and the like, the combination of a picture projecting device; a relay device actuated when the shot is fired; a magnetic clutch device on the picture projecting device for normally connecting the said picture projecting device to the source of power; an electromagnet; a source of electrical energy in circuit with said magnet; a contact device also in circuit with said magnet and normally closed but arranged to open when the relay is actuated; an armature actuated by the deenergizing of the magnet so as to deenergize and release the magnetic clutch on the picture projecting device; a band brake on said picture project- 115
26. In target apparatus for use with kinematographs and the like, the combination of a picture projecting device; a relay device actuated when the shot is fired; a magnetic clutch device on the picture projecting device for normally connecting the said picture projecting device to the source of power; an electromagnet; a source of electrical energy in circuit with said magnet; a contact device also in circuit with said magnet and normally closed but arranged to open when the relay is actuated; an armature actuated by the deenergizing of the magnet so as to deenergize and release the magnetic clutch on the picture projecting device; a band brake on said picture project- 120
27. In target apparatus for use with kinematographs and the like, the combination of a picture projecting device; a relay device actuated when the shot is fired; a magnetic clutch device on the picture projecting device for normally connecting the said picture projecting device to the source of power; an electromagnet; a source of electrical energy in circuit with said magnet; a contact device also in circuit with said magnet and normally closed but arranged to open when the relay is actuated; an armature actuated by the deenergizing of the magnet so as to deenergize and release the magnetic clutch on the picture projecting device; a band brake on said picture project- 125

ing device; an electromagnet controlling said band brake actuated when the aforementioned armature is released; and means for restoring the apparatus to its normal operating condition after a predetermined interval of time and thereby automatically re-starting the picture projecting device.

In testimony whereof, we have signed our

names to this specification in the presence of two subscribing witnesses.
